United States Patent Office

Des. 189,443
Patented Dec. 13, 1960

189,443

CARRYING AND DISPLAY CASE FOR TELEPHONE SETS

Henry G. Turner, Atlanta, Ga., assignor to American Telephone and Telegraph Company, New York, N.Y., a corporation of New York

Filed May 9, 1960, Ser. No. 60,505

Term of patent 14 years

(Cl. D87—5)

FIG. 2

Fig. 1 is a front perspective view of a carrying and display case for telephone sets showing my new design; and

Fig. 2 is a rear perspective view thereof.

The bottom of the case is substantially plain.

I claim:

The ornamental design for a carrying and display case for telephone sets, as shown and described.
